CLAIM

The ornamental design for an SIP based flash memory card, as shown and described.

DESCRIPTION

FIG. 1 is a perspective view of an SIP based flash memory card according to embodiments of the present invention.

FIG. 2 is a bottom view of an SIP based flash memory card according to embodiments of the present invention.

FIG. 3 is a view of a first end of an SIP based flash memory card according to embodiments of the present invention.

FIG. 4 is a view of a first side of an SIP based flash memory card according to embodiments of the present invention.

FIG. 5 is a view of a second side of an SIP based flash memory card according to embodiments of the present invention.

FIG. 6 is a view of a second end of an SIP based flash memory card according to embodiments of the present invention; and,

FIG. 7 is a top view of an SIP based flash memory card according to embodiments of the present invention.

The broken lines on the drawings are for illustrative purposes only and form no part of the claimed ornamental design.
